DESIGN FOR A WEIGHING SCALE

Bernard M. Thiel, Mishawaka, Ind.

Application April 13, 1945, Serial No. 118,971

Term of patent 3½ years

(Cl. D52—10)

To all whom it may concern:

Be it known that I, Bernard M. Thiel, a citizen of the United States, residing at Mishawaka, in the county of St. Joseph, State of Indiana, have invented a new, original, and ornamental Design for a Weighing Scale, of which the following is a specification, reference being had to the accompanying drawing, forming part thereof.

Fig. 1 is a top plan view of the weighing scale, showing my new design.

Fig. 2 is a side elevation of the scale.

Fig. 3 is an end elevation of the scale.

I claim:

The ornamental design for a weighing scale, as shown.

BERNARD M. THIEL.
